DESIGN FOR A CUP HANGER

James P. Burke, Struthers, Ohio, assignor to James E. Cronan, Flint, Mich.

Application June 13, 1941, Serial No. 101,444

Term of patent 14 years

To all whom it may concern:

Be it known that I, James P. Burke, a citizen of the United States, residing at Struthers, in the county of Mahoning and State of Ohio, have invented a new, original, and ornamental Design for a Cup Hanger, of which the following is a specification, reference being had to the accompanying drawing, forming part thereof.

Fig. 1 is a top plan view of the cup hanger showing my new design; and

Fig. 2 is a side elevational view thereof, drawn in half-section.

I claim:

The ornamental design for a cup hanger substantially as shown.

JAMES P. BURKE.
